DRAIN CLEANER

Henry Baden, Cape Girardeau, Mo.

Application May 10, 1934, Serial No. 724,999

4 Claims. (Cl. 285—44)

This invention relates to a drain cleaner and it aims to provide a novel means whereby water under full force is delivered to the drain to wash the same and remove any stubborn stoppage therein.

It is aimed to provide a novel construction attachable to a faucet or the like and having a flexible section of hose provided with a nozzle for attachment thereto of various elements to enable the water to be directed into various drains.

The more specific objects and advantages will become apparent from a consideration of the description following taken in connection with accompanying drawings illustrating an operative embodiment.

In said drawings:

Figure 1 is a view in side elevation of the invention, showing the same in use in connection with a basin or lavatory;

Figure 2 is an enlarged longitudinal sectional view, partly broken away, of the improvement alone;

Figure 3 is a view showing the improvement in elevation and as using a different form of nozzle;

Figure 4 is a view similar to Figure 3 showing a further form of nozzle;

Figure 5 is a view of the device illustrated with a still further form of nozzle;

Figure 6 is a detail view showing another form of nozzle connected to the device;

Figure 7 is a detail sectional view taken on the line 7—7 of Figure 6, and

Figure 8 is a detail section of a still further modified form.

Referring specifically to the drawings, and first to Figures 1 and 2, the device comprises a suitable length of rubber or flexible hose 10 equipped with a coupling 11 at one end thereof for detachable engagement with the outlet end of a spigot or faucet 12. Said coupling 11 accommodates a washer 13 of rubber, which may vary in size according to the size of the spigot, and through which the spigot is forced. In addition, a screw 14 may be threaded through the coupling 11 and operated to bind against the spigot to more effectively hold the device in place.

Said spigot is shown as associated with a lavatory 15 of which 16 is the drain pipe. At the end opposite the coupling 11, the hose is equipped with a rotatable coupling ferrule 17 having interior screw-threads at 18. Detachably screw-threaded to said threads 18 is a nozzle 19 provided with a flange 20 facilitating turning of the nozzle. Said nozzle may be of any suitable length

and has exterior screw-threads at 21 and interior screw-threads at 22. A relatively large metallic head 23 is adjustably threaded on the exterior of the nozzle 19, and has an exterior knurled portion 24. The nozzle extends through a relatively large disk 25 of sponge rubber which bears against the head 23 and also surrounding the nozzle and bearing against the sponge rubber disk 25 is a disk 26 made of laminations of rubber, somewhat harder than sponge rubber although fully flexible.

A supplemental nozzle 27 is screw-threaded exteriorly and engaged with the screw-threads at 22, and at its free end has a hook 28 secured thereon.

As shown in Figure 1, the supplemental nozzle 27 extends into the waste pipe 16 and the hook 28 engages a part of the usual spider 29 therein. It will be noted that the rubber 26 effects a seal about the discharge pipe 16 and that the rubber may be compressed sufficiently to enable the hook 28 to engage the spider 29 and then assume its original position, effectively holding the hook in engagement with the spider.

With the device attached as shown in Figure 1, upon the faucet 12 being opened, the water with full force will pass through the device and be discharged through the supplemental nozzle 27, the discharge being against the hook 28, which serves to so coat with the stream of water discharged as to impart a swirling motion thereto in combination with the inner wall of the pipe 16, to effect an efficient washing and dislodgment of any matter tending to stop the pipe 16.

In Figure 1, the device is shown in connection with a lavatory but it is obvious that it may be used with other articles of plumbing and particularly sinks and bath-tubs.

In Figure 3, the device is used to wash the overflow space such as 30 in lavatories and bath-tubs, to which end, a different form of supplemental nozzle 31 is used instead of the supplemental nozzle 27, the same having a screw-threaded portion 32 detachably engaging the screw-threads 22. The nozzle 31 is passed through an opening 33 in the wall of the lavatory or bath-tub.

In Figure 4, a different form of nozzle 34 supplants that used at 31, it differing from the nozzle 31 by having a more pronounced terminal 50 crook 35 to better coat with the different form of overflow space 36 of the lavatory, bath-tub or the like.

In instances where the plumbing has a channel or pipe 37 through a wall for drainage purposes,

an extension nozzle 38 is screw-threaded at 39 into the screw-threads 22 and disposed in the passage 37. At the other end of pipe 38, the aforesaid extension nozzle 27 is connected 5 through the medium of a sleeve coupling 40, engaging the exterior screw-threads on the nozzle 27 and on the pipe 38 as at 41. The hook 28 in this instance, serves only for impingement of water against the same to impart a swirling 10 motion thereto in combination with the wall of the chamber 37.

In the modified form shown in Figures 6 and 7, the nozzle 19 and parts attached thereto are omitted. The coupling 42 on the discharge end 15 of the pipe here designated 43, has external screw-threads 44 which are engaged by a ferrule or thimble 45 retaining a nipple 46 in place through the overlapping of flanges 47 on the parts 45 and 46, a washer being interposed between such 20 flanges and coupling as at 48. Nipple 46 is interiorly screw-threaded, and detachably engaged by screw-threads 49 of an extension nozzle 50 to which an arm 51 is secured, mounting a V-shaped deflector 52 in the line of discharge from the 25 nozzle 50. This form of the invention is used principally in connection with basement and outside sewers and the deflector 52 serves to divide the water into a plurality of streams for more effective action.

30 In Figure 8, a modified form is used where the hose conveys water a long distance and when short crooks occur or a narrow space must be entered. In this form, a thimble 45 retains a nipple 53 and interiorly screw-threaded in such 35 nipple is the extension nozzle 27, equipped with the hook 28 functioning as previously described.

Various changes may be resorted to provided they fall within the spirit and scope of the invention.

40 I claim as my invention:—

1. A device of the class described having a flexible hose, means at one end thereof for attachment to a spigot, a coupling at the other end thereof, an outlet nozzle secured to said coupling, 45 a head on said nozzle, a supplemental nozzle adapted to extend into an outlet of materially

larger cross sectional area than the supplemental nozzle, connected to the first mentioned nozzle, a hook on the supplemental nozzle to engage the spider in said outlet, and compressible material at a distance from said hook engageable with said head and about the outlet, said material being compressible to an extent to permit operative attachment and detachment of the hook and the spider through tilting of the head and connected parts.

5 2. A device of the class described comprising a flexible hose, means at one end thereof for attachment to a spigot, a nozzle at the other end thereof adapted for communication with a drain or the like, a head screw-threaded on said nozzle, packing material disposed about the nozzle and in engagement with said head, a supplemental nozzle detachably secured to the interior of the first mentioned nozzle, and a deflector for water discharged through the device carried by 15 the nozzle and arranged in the line of discharge, said deflector being in the form of a hook to engage a spider in an outlet.

20 3. A device of the class described comprising a flexible hose having screw-threads at the discharge end, a ferrule in engagement with said screw-threads, a nipple, said nipple and ferrule having overlapping flanges, a discharge nozzle screw-threaded in said nipple and a spreader for the discharged water carried by the nipple and 25 arranged in the path of discharge of the water.

25 4. A device of the class described comprising a flexible hose, means at one end thereof for attachment to a spigot, a nozzle at the other end thereof adapted for communication with a drain or the like, a head screw-threaded on said nozzle, packing material disposed about the nozzle and in engagement with said head, a supplemental nozzle, an elongated nozzle between the first mentioned nozzle and supplemental nozzle screw-threaded within the first mentioned nozzle, the supplemental nozzle having a deflector for discharged water, and a sleeve connecting the supplemental nozzle and second mentioned nozzle.

40 45 HENRY BADEN.
